TUBULAR CAN HOLDER OR
SIMILAR ARTICLE

John Aldape, 1300 Santa Paula,
Boise, Idaho 83702

Filed Sept. 30, 1968, Ser. No. 13,768

Term of patent 14 years

Int. Cl. D7—99

U.S. Cl. D49—35

FIG. 1

FIG. 2

FIG. 3

FIGURE 1 is a front isometric view of a tubular can holder, showing my new design;

FIGURE 2 is a side elevational view thereof, with the protective cover in a raised position; and

FIGURE 3 is a top plan view thereof.

The broken lines representing the waste can are shown for illustrative purposes only.

I claim:

The ornamental design for a tubular can holder or similar article, substantially as shown and described.
